UNITED STATES PATENT OFFICE

ROBERT M. CRITCHFIELD, OF ANDERSON, INDIANA, ASSIGNOR TO DELCO-REMY CORPORATION, OF ANDERSON, INDIANA, A CORPORATION OF DELAWARE

HORN PROJECTOR

Application filed May 31, 1930. Serial No. 458,611.

This invention relates to sound projectors or trumpets adaptable for use with sounding signal devices and is particularly adaptable to that class of sound signal known as the air 5 tone horn.

It is one of the objects of the instant invention to provide a sound product closely approaching the timber of a cornet or bugle.

A further object of the instant invention 10 is to increase the effective length of the sound conduit.

A further object of the invention is to provide a purer air tone by damping out objectionable mechanical sounds.

15 Further objects and advantages of the present invention will be apparent from the following description, reference being had to the accompanying drawings wherein a preferred embodiment of one form of the present invention is clearly shown.

In the drawings:

Fig. 1 is a longitudinal sectional view of an improved trumpet including the instant invention.

25 Fig. 2 is a transverse sectional view thereof, substantially as indicated by the line and arrows 2—2 of Fig. 1.

With particular reference to the drawings, 20 indicates a collar member forming part 30 of the housing of a magnet motor device of the usual vibratory horn, and in the illustrated embodiment provides a machined surface 21 for cooperation with a vibratory member or piston 23 secured to the armature 35 rod 24 of the magnet motor, by a nut 25 and lock washer 26. The magnet motor is not illustrated in full, but as is well known to those skilled in the art, the magnet motor operates to reciprocate the piston member 23 to and from the face 21 whereby rapid stopping of an air column is accomplished.

Secured to the collar member 20 in any 45 desirable manner, there is a trumpet or projector 30 provided with a clamping nut 31 that may be threaded into the collar 20 as generally indicated at 32. The projector 30 terminates in a bell 33 that operates with the face 21 to define an air column particularly 50 responsive to the sound waves set up within the trumpet by the operating magnet mo-

tor. In sounding signals of the illustrated type, it is desired to produce a tone product of low pitch, and that necessitates an elongated projector, but since a sounding signal device with a long projector is more expensive in manufacture, less convenient to mount, and is of less desirable appearance, means have been provided for increasing the effective length thereof without increase of its physical dimension. Due to the method 60 of stopping the air column within the trumpet 30, and due to the closeness of adjustment that must be maintained between the piston 23 and face 21 of the collar member, there is apt to be present in the sound 65 product of the signal device, mechanical noises that are frequently amplified by the projector 30, and it is therefore desirable to dampen out those mechanical noises so as to purify the tone of the signal device and to 70 better simulate a true air tone.

These problems have been solved in the instant invention, by providing the trumpet 30 with a spiral ribbon 40 forming a partition throughout the greater portion of its 75 length, and dividing the air column into a pair of substantially gyratory paths 41 and 42. The ribbon 40 is inserted within the projector as illustrated so that the edges of the ribbon are in contact with the side walls of 80 the trumpet where they may be secured in any desirable manner as by soldering or the like. In the illustrated embodiment the spiral partition stops short of the bell 33 as illustrated at 43, and the trumpet is spun 85 outwardly to form a rib or ridge at 44 at a convenient point between the end 43 of the ribbon and the bell 33, so as to receive a foraminous grill or screen 45. The grill prevents the entrance of foreign material within 90 the projector and operates to provide a more pleasing appearance than would otherwise obtain.

When a sounding device is fitted with the improved projector the sound waves impressed thereon will be conducted along the throat of the projector where they will engage the spiral partition 40, and thus be conducted along either one of the gyratory paths 41 or 42 and thence outwardly in the usual manner.

This of course, increases the effective length of the air column within the projector, in that the sound waves are caused to follow a longer path by reason of the spiral partition, then 5 they would otherwise do without it. The partition member within the trumpet tends to load the same and thus reduces its fundamental of vibration, and thence the same is less responsive to high pitch mechanical vibrations set-up by the vibratory means.

10 While the form of embodiment of the present invention as herein disclosed, constitutes a preferred form, it is to be understood that other forms might be adopted, all coming 15 within the scope of the claims which follow.

What is claimed is as follows:

1. In a sounding device the combination comprising, an uninterrupted sound conduit, 20 and means dividing the air column therein into a pair of gyratory paths increasing the effective length of said conduit.

2. The combination comprising, a sound conduit, means supporting the conduit and operating therewith to define an air column 25 of definite length, and means dividing the conduit into a plurality of substantially parallel branches to increase the effective length of said air column.

3. The combination comprising, a sound 30 conduit, means supporting the conduit and operating therewith to define an air column of definite length, and means forcing the sound waves through said conduit to follow a plurality of gyratory paths whereby the effective 35 length of said conduit is increased.

4. The combination comprising, a sound conduit, means supporting the conduit and operating therewith to define an air column 40 of definite length, and means dividing the air column into a pair of gyratory paths, whereby the effective length thereof is increased.

5. The combination comprising, a sound conduit, means supporting the conduit and operating therewith to define an air column of 45 definite length, a twisted ribbon within the conduit for increasing the effective length of the same.

6. The combination comprising, a sound 50 conduit, means supporting the conduit and providing means for setting the air column thereby defined into audible vibration, and means carried by the sound conduit increasing the effective length thereof and damping out 55 mechanical sounds, said last means comprising a partition member dividing the said air column into a pair of substantially helical sound paths.

7. The combination comprising, a sound 60 conduit, means supporting the conduit and providing means for setting the air column thereby defined into audible vibration, a twisted ribbon dividing the air column into 65 a pair of gyratory paths, said ribbon operating to increase the effective length of said air

column and to dampen out substantially all mechanical sounds.

8. The combination comprising, a sound conduit, means supporting the conduit and operating to define an air column of definite 70 length, a twisted ribbon disposed along the axis of the conduit dividing the air column into a plurality of sound paths.

In testimony whereof I hereto affix my signature.

ROBERT M. CRITCHFIELD.
